COVER FOR WASHING MACHINES AND
THE LIKE

Clarence G. Frantz, Cleveland Heights, Ohio, assignor to The Apex Electrical Manufacturing Company, Cleveland, Ohio, a corporation of Ohio

Application December 16, 1948, Serial No. 65,666

3 Claims. (Cl. 220—85)

1

This invention relates to covers for washing machines and the like, and more particularly to a cover of this type having improved hook means for supporting the cover when not in use.

It has been common practice to provide removable covers for tubs of washing machines, particularly washing machines of the wringer type, and to affix a hook to the cover whereby the cover may be supported by a top edge portion of the tub when not in use. The hook is generally formed of a metal strip bent to U form with one leg of the strip abutting the under side of the cover and riveted thereto adjacent the cover edge and the other leg of the U which is adapted to engage the top edge portion of the tub is sheathed with rubber or the like. However, the rivet head is exposed and it frequently happens that in positioning the hook on the top edge of the tub, the tub side walls are scratched, and the same condition occurs if the hook is bolted to the tub. Of course, the hook could be welded to the cover but this requires a subsequent metal finishing operation to provide a cover having a satisfactory appearance. All the aforesaid means of attaching the hooks require tools on the production line and also in the event it is desired to subsequently replace the hook. Further, riveting a metal hook to the cover is relatively expensive in that the hook must be shaped to U form, one leg of the hook must be perforated, the hook must be riveted to the cover, and a protective sheath must be applied to the hook.

I have devised a hook for covers of this type which avoids the aforementioned disadvantages and which effects a substantial saving in cost. According to the invention, a circular hole is formed in the cover adjacent the cover edge. A hook element formed entirely of rubber comprises a ring which is peripherally grooved to form top and bottom flanges and a hook which extends generally at a right angle from the bottom flange. To attach the hook element to the cover it is merely necessary to force the top flange through the cover hole and permit the ring element to assume its normal shape whereby the flanges engage a ring shaped area of the cover bounding the hole to detachably secure the element to the cover.

It is a primary object of the invention to provide a cover for washing machines or the like having an improved hook element for supporting the cover when not in use.

Another object of the invention is to provide a cover of the above type having a hook element formed entirely of rubber and which can be easily

2

and quickly secured to and removed from the cover without the use of tools.

Another object of the invention is to provide a cover of the above type having a hook element which is relatively inexpensive to manufacture and assemble with the cover.

Another object of the invention is to provide a cover of the above type having a hook element without any metal parts which might scratch a tub supporting the cover and having a portion which acts as a spacing and cushioning means between the tub and cover.

Other objects of the invention and the invention itself will become increasingly apparent from 15 a consideration of the following description and drawing wherein:

Figure 1 is a fragmentary bottom perspective view of a cover embodying the invention;

Figure 2 is a fragmentary top plan view of the 20 cover shown in Fig. 1;

Figure 3 is a fragmentary bottom plan view of the cover shown in Fig. 2; and

Figure 4 is a sectional view showing the manner 25 in which the hook element engages the tub of a washing machine or the like.

Referring now to the drawings, I have indicated 30 at 19 a conventional cover for the tub of a wringer type washing machine. The cover is preferably upwardly dished and provided with a peripheral rubber seating bead 11. Adjacent the edge of the cover a circular hole is formed in a suitable manner as by a punching die.

A hook element, generally indicated at 12, is 35 formed of molded rubber and comprises a ring form portion having a peripheral groove formed therein to provide a top flange 13 and a bottom flange 14. The groove is formed by suitably shaping the mold for the hook element. The term "rubber" as used herein is intended to include any suitable material having the characteristics of rubber whether the material comprises natural rubber, synthetic rubber or both. Extending generally at right angles from the bottom flange 14 is a hook portion 16 preferably 40 having a flat face 17 to minimize any tendency of the cover to rock when supported by the tub as illustrated in Fig. 4. The hook portion 16 has a toe 18 and preferably the hook portion increases in cross-sectional area proceeding towards the ring portion.

Hole 19 in the hook element is of sufficient size to permit distortion of the ring portion of the element under manual pressure whereby top flange 13 may be projected through the cover 45 hole and assume its normal shape to overlie a

ring shaped area of the cover bounding the hole. The bottom flange 14 will then abut a preferably larger ring shaped area of the cover whereby the hook element is firmly and detachably secured to the cover by the flanges. The aforementioned manner of mounting the hook element on the cover is relatively quick, avoids the use of tools on the assembly line, such as riveting apparatus, and provides a sufficiently firm engagement with the cover to prevent shifting of the hook element from a properly adjusted position. In the event it is desired to replace the hook element, this can be quickly and easily effected without the use of tools.

Numerous rubber materials are available which will permit the ring portion of the element to be deformed under reasonable manual pressure and at the same time prevent any substantial bending of the hook portion 16 due to the weight of the cover, although the bending tendency can be largely controlled by providing a hook portion of suitable cross-sectional area and shape.

It will be noted by reference to Fig. 4 that the tub is provided with a radially inwardly extending top flange forming a seating surface for the cover peripheral portion, the cover bead 11 being adapted to seat in the groove of this flange. It is obviously desirable that the hook portion 16 be disposed as close to the cover edge as possible consistent with clearing the inner edge of the tub top flange when the cover is in place. In prior practice wherein a metal hook is riveted to the cover, it frequently happened that the exposed rivet head would scratch the tub when locating the hook to engage the tub flange. It is apparent that this could not occur with my improved hook element.

The cover when supported by the hook will tend to swing towards and engage the tub at its lower portion, and particularly in the case of tubs having slightly sloping rather than vertical side walls, the ring portion of the hook element acts as a cushioning and spacing means for the cover in that the ring portion diametrically opposite the hook can engage the tub side wall.

When the cover is in place the hole 19 provided in the ring portion will permit a finger grip on the cover or can receive the hooked end of a conventional drain hose provided in some instances on washing machines.

I have found that a substantial saving in cost, in addition to the advantages pointed out, can be effected by employing a hook element of the type described compared to a conventional metal hook.

I wish it to be understood that I do not desire to be limited to the exact details of construction shown and described, for obvious modifications will occur to a person skilled in the art.

10 What I claim is:

1. The combination with a cover for washing machines and the like having a portion adjacent the cover edge which is provided with a hole and is adapted to be substantially horizontally disposed with the cover in operative position, of a hook element formed entirely of rubber secured to said cover portion, said element comprising a ring form portion having a peripheral groove therein forming top and bottom flanges, a hook portion extending from the bottom flange and generally normal thereto, the ring portion being manually deformable whereby the top flange may be projected through the cover hole permitting a ring form area of said cover portion bounding the hole to be gripped between the flanges, and the bottom flange being of sufficient radial extent and thickness to serve as a cushioning and spacing means preventing contact between the cover and the machine tub side wall adjacent the hook element when the cover is supported by the hook portion engaging the top edge of the tub.

2. The combination as described in claim 1 and wherein the hook portion has a toe at the end thereof, and the hook portion increases in cross sectional area from the toe towards the ring portion.

3. The combination as described in claim 1 and wherein the hook portion is sufficiently rigid to support the weight of the cover without substantial bending of the hook portion.
